CLOTHES HANGER

William L. Niclaus, 170 Knoll Road,
Parsippany, N.J. 07005

Filed May 27, 1975, Ser. No. 580,730

Term of patent 3½ years

Int. Cl. D6—08

U.S. Cl. D6—255

FIG. 1 is a front elevational view of a clothes hanger showing my new design;

FIG. 2 is a side elevational view taken from the right of FIG. 1;

FIG. 3 is a bottom plan view thereof; and

FIG. 4 is an enlarged sectional view taken on line 4—4 of FIG. 1.

I claim:

The ornamental design for a clothes hanger, as shown and described.
